UNITED STATES PATENT OFFICE.

CHARLES H. SHAFFER, OF ROCKFORD, ILLINOIS, ASSIGNOR OF ONE-HALF
TO JONES, WOODRUFF & CO., OF SAME PLACE.

SPRINKLER.

SPECIFICATION forming part of Letters Patent No. 367,322, dated July 26, 1887.

Application filed September 20, 1886. Serial No. 214,098. (No model.)

To all whom it may concern:

Be it known that I, CHARLES H. SHAFFER, a citizen of the United States, residing at the city of Rockford, in the county of Winnebago and State of Illinois, have invented a new and useful Sprinkler, of which the following is a specification.

This invention relates to a class of sprinklers known as the "rotary sprinkler." It is especially designed to be employed in systems of automatic fire-extinguishers, but capable of other applications. Its object is the equal distribution of water over an area within its capacity; and it consists in the improved features of construction hereinafter described and set forth.

In the accompanying drawings, Figure 1 is an elevation of my improved sprinkler. Fig. 2 is an under face view of the rotary distributing-wheel. Fig. 3 is a vertical central section in isometrical perspective, and Fig. 4 is an isometrical representation of the lower end portion of the yoke mechanism.

The valve-case 1, which is the nozzle to the sprinkler, is of tubular form, and its end portion is screw-threaded to connect with the water-supply pipe, and is also provided with a nut-formed projection, 2. A valve-seat, 3, with central valve-opening, is fixed in the extreme inner end of the nozzle. The nozzle is also provided with a transverse bridge-bearing, 4, connecting opposite sides of the nozzle, and is bored in the axial center thereof to support a valve-stem, 5, in a manner to permit of a free rotary and endwise movement in its axial support. A valve, 6, with suitable facing, 7, preferably of soft metal, is fixed on the end of the valve-stem to engage the valve-seat. The extreme outer end portion of the nozzle outside of the nut-formed portion is produced in curve conic form, as clearly shown, for a purpose to appear hereinafter.

The distributing portion 8 of the sprinkler is of disk form, having its edges slotted radially, and the tooth-like portions 9 of its edge are curved upward in disk or bowl form, and are each twisted to place their peripheral edge on a tangent to a circle of less diameter than the diameter of the distributer, producing a curved

reaction-bucket to receive the water discharged through the nozzle to cause it to rotate and distribute the water.

The central portion of the distributer is provided with outlet-openings having inclined lips 10 depending therefrom and overlapping their respective openings on the outer face of the distributer. The inclination of the lips 10 with relation to the curved buckets are such as to co-operate to impart a rotary motion to the distributer. This distributer 8 is fixed to the projecting end of the valve spindle at the outlet-opening of the nozzle in such position thereon that the inner bowl-formed portion of the buckets will overlap the extreme curved conic-formed portion of the nozzle, for a purpose to appear hereinafter.

A spiral spring, 11, is placed on the valve-stem between its bridge support and the distributer, and its spring action tends to relieve the valve from its seat.

Hangers 12 and 13 are formed with hook ends 14, to engage the projecting portions of the nut 2, and the depending end of the hangers are provided with outward-projecting hooks 15, to receive a clasp-bar, 16, to connect the lower ends of the hangers. A bridge-tree, 17, is supported at one end on projections 18 on the inner face of the hangers 12, and its other end is supported on an abutment, 19, placed on the inside of the hanger 13, having a foot support on a hook, 20, projecting from the lower end inner face of the hanger. The bridge-tree is provided with a valve-adjusting screw, 21, having a screw-threaded connection with the bridge in position to engage the axial center of the valve-stem at its projecting end, and serves to press the valve to its seat firmly.

The clasp-bar 16 is composed of two parts, with its meeting ends to overlap, and its outer ends are of hook form to embrace the hook ends 15 of the hangers. Its center portion is of open form to admit a screw-driver or key to operate the valve-adjusting screw. The meeting ends of the two-part clasp-bar overlap each other, and their overlapping ends are joined by a solder having a low-temperature melting-point.

In the use of my improved sprinkler, the nozzle is suitably connected with the water-

supply, the hangers are put in place on the nozzle, the bridge-tree is then put in place within the hangers, and the clasp-bar put in place on their lower ends. The valve is then adjusted to its seat by means of the adjusting-screw, which fits the apparatus for use.

My improved nozzle is capable of use in fire-protection systems in which the water supply pipes are filled with water, or from which the water is excluded by air contained within the pipes, in both of which instances the spiral spring 11 may be omitted. It is also capable of use in what is known as the "vacuum system," in which both air and water are excluded from the water-supply pipes until automatically admitted by the action of the fire or heat, in which instance the spring 11 will open the valve and admit air to the vacuum-pipes. It will be observed that the hook-support 20 of the abutment 19 and the connection of the bridge-tree bearing on the abutment are in independent vertical planes in such relation to each other that when the clasp-bar 16 is separated force on the bridge-tree, either by the action of the spring 11, water, or air-pressure on the valve, will operate to spread the hangers, throw them from their connection with the nozzle, permit the bridge-tree to drop from its supports, and the valve to open.

When my improved sprinkler is in place complete, heat sufficient to melt the solder will permit the clasp-bar to separate and open the valve, and water will flow through the nozzle against the distributor and cause it to rotate and deliver the water through the outlet-openings in its central portion, and also from the openings between the curved reaction-buckets.

It will be noticed that in the rotations of the distributor a portion of the water discharged from the reaction-buckets will be thrown against the curved conic surface of the nozzle, and will be deflected upward and outward in a manner to distribute the discharged water substantially uniform over the area within its capacity. When the apparatus is placed near the ceiling of the apartment, the upward outward throwing of the water by the action of the reaction-buckets and the curved conic ends of the nozzle will serve to wet the ceiling, and also to cover a greater area.

I claim as my invention—

1. The combination of a nozzle, a valve-seat within the nozzle, a valve to engage the valve-seat mounted on one end of and having an axial stem-support, and a rotary distributor mounted on the other end of said valve-stem, to rotate therewith, and composed of a single piece comprising a disk having a circular series of openings, inclined lips depending therefrom beneath said openings, and a radial series of reaction-buckets formed by the verti-

ally bent and twisted peripheral portions having their edges tangential to the disk, substantially as set forth. 65

2. The combination, with a nozzle having its lower external part formed to present a curved conic delivery end extension, of a valve-seat within said nozzle, a valve to engage the valve-seat mounted on one end of and having an axial support, a rotary distributor mounted on the other end of said valve-stem to rotate therewith, and composed of a single piece comprising a disk having a slotted peripheral portion extending beyond the extension and bent vertically and twisted to present reaction-buckets adjacent to the curved conic portion, and having their edges tangential to the disk, and a circular series of openings formed in said disk, and lips depending therefrom beneath said openings, substantially as set forth. 70 75

3. The combination, with the nozzle having the internal valve-seat and bridge, of a spindle-bearing in said bridge to rotate and move longitudinally therein, a valve mounted on the upper end of said spindle, a sprinkling-disk secured to the other end of said spindle, a spring interposed between said disk and bridge and adapted to move the valve from its seat, and a hanger and movable bridge supporting the lower end of the spindle to hold the valve on its seat, and a solder for holding said hanger in position, substantially as set forth. 80 85 90

4. The combination, with the nozzle having the internal valve-seat and bridge, of a spindle located in said bridge to rotate and move longitudinally therein, valve on one end of said spindle and sprinkling disk on the other end, a spring interposed between said bridge and disk to throw the valve away from its seat, a horizontal bridge sustaining the lower end of said spindle, an adjusting screw bearing in said last-mentioned bridge, hangers of the valve-supporting yoke, and a clasp-bar 105 having a solder-connection of a low-melting temperature and recessed to expose the end of the screw, substantially as set forth.

5. The combination of a nozzle, a valve seat, a valve to engage said seat mounted on one end of and having an axial stem-support adapted to have a longitudinal play, a spring adapted to throw the valve from its seat, hangers depending from the nozzle, the clasp-bar having a solder-connection, a horizontal bridge sustaining said stem and valve, but formed separate therefrom, said bridge having a free connection with a hanger at one end and a free abutment-connection with the hanger at the other end, and sprinkling disk located on the lower end of said stem-support, substantially as set forth. 115 120
